UNITED STATES PATENT OFFICE.

DAVID W. KENDALL, OF GRAND RAPIDS, MICHIGAN, ASSIGNOR TO THE PHOENIX FURNITURE COMPANY, OF SAME PLACE.

DESIGN FOR A CHAIR.

SPECIFICATION forming part of Design No. 27,597, dated August 31, 1897.

Application filed July 24, 1897. Serial No. 645,870. Term of patent 3½ years.

To all whom it may concern:

Be it known that I, DAVID W. KENDALL, a citizen of the United States, residing at Grand Rapids, in the county of Kent and State of Michigan, have invented and produced a new and original Design for Chairs, of which the following is a specification, reference being had to the accompanying drawing, showing a part thereof.

10 The figure is a perspective of my chair, which I deem sufficient to fully illustrate my design.

15 The leading features of my design consist of broad oblong arms A, supported upon square legs B, with the outer edge of the arms supported by braces C, attached at end to the legs and, inclining outward, secured at the other end to the shelves, as shown, and a series of square spindles D, extending from 20 the arms down past the seat E, to which they are attached, and to the girths F, to which the

lower ends are secured, said girths being securely attached to connect and support the front and back legs of the chair.

The two side frames of the chair are connected and securely bound together by the cross-girths G, secured to the girths F, at the center by the seat E, in the usual manner, and at the arms by the inner back corner thereof being secured to the back H. The 25 side frames are further strengthened by the girth I, substantially as shown. The junction of the upper ends of the spindles may be a scroll, as J, or other suitable design.

What I claim as new is—

20 The design for a chair substantially as shown and described.

DAVID W. KENDALL.

In presence of—

ANDREW ALLGIER,
I. J. CILLEY.
